W. G. WINANS

GARAGE DOOR HOLDER

Filed Dec. 13, 1926

Attorney

UNITED STATES PATENT OFFICE.

WESLEY G. WINANS, OF DETROIT, MICHIGAN.

GARAGE-DOOR HOLDER.

Application filed December 13, 1926. Serial No. 154,476.

This invention relates to garage door holders and relates particularly to devices for holding open (or partially open) a hinged garage door.

5 An object of the invention is to so mount a device for holding open a garage door as to minimize strains upon the hinges of the door and adapt said device for use as a handle for operating the door.

10 Another object is to provide a door holder having a provision for holding the door either fully opened or in any desired intermediate position.

15 A further object is to provide a door holder for garage doors fully operable from the interior of the garage.

20 A still further object is to adapt a device for holding open a garage door to be readily released from the frame of the door so as to permit a free swinging of the door independently of said device.

25 It is an object also to adapt a door holder to be mounted in its position of use quickly and without the necessity of a step-ladder or the like.

These and various other objects are attained by the construction hereinafter described and illustrated in the accompanying drawing wherein;—

30 Figure 1 is an interior view of a garage door and its frame showing the installation thereupon of the herein described holder.

35 Figure 2 is a sectional view of the same taken upon line 2—2 of Figure 1 and showing various positions of the door and holder.

Figure 3 is an elevational view partly in section on line 3—3 of Figure 4 of a bracket upon the door and a holding rod engaging said bracket.

40 Figure 4 is a fragmentary side view of the outer end of said holding rod, sectionally showing said bracket.

In these views the reference character 1 designates a door hingedly mounted in a suitable frame 2 and controlling access to a 45 garage or other building. Upon the upright 3 to which the door is hinged there is mounted a bracket member 4, and a co-acting bracket member 5 is secured to the in-

terior face of the door approximately midway of the height of the door. The bracket 4 has a lug 6 projecting therefrom formed with an opening 7 in which is pivotally en-

50 gaged the down-turned inner end 8 of a holding bar 9. The bracket 5 is formed with a projecting lug 10 formed with an

opening 11 in which said bar is slidably mounted. The outer end of said bar is upturned as indicated at 12 to form an abutment engageable with the lug 10 to limit 60 the opening travel of the door.

The opening 11 of the lug 5 has a notch 13 extending from its lower edge and the outer end of the bar 9 is reduced in width in its lower portion 14, and said portion is 65 notched as indicated at 15. When the door is swung transversely to the frame 2 so as to fully clear the doorway, the abutment 12 engages the lug 10 to restrain the door from further opening movement and the 70 notches 15 and 13 of the bar and said lug inter-engage to further restrain the door from opening movement (and from rattling), and to also restrain the door from movement inward.

75 To permit the door to be secured in any intermediate position the lug 5 carries a set screw 16 which is adapted to project into the opening 11 of said lug and to be clamped against the bar 9 to prevent relative sliding of said bar and lug to thereby hold the door rigid.

80 It is a highly desirable feature of said construction that the door may be released from its opened position, in which the notches 13 and 15 are inter-engaged, without the necessity of the operator leaving the garage. That is to say, the operator by exerting a slight upward pressure upon the inner portion of the bar 9, can lift said bar sufficiently to disengage the notches 13 and 15, whereupon said bar may serve as a handle for pulling the door shut. It is also evident that said bar may serve as a handle for actuating the door to its opened position.

85 In case it is desired to retain the door in any intermediate or partially opened position, it is necessary only to tighten the set screw 16 in such position of the door, whereupon the rod 9 will form a rigid connection 100 between the door and frame.

If it be desired to swing the door beyond its fully opened position or for any other reason to render the door independent of the holder, this may be accomplished by 105 simply lifting the inner end of the bar 9 so as to disengage its pivot portion 8 from the bracket member 4.

110 It is to be noted that the engagement of the described holder with a portion of the door substantially midway of its height tends to equalize such strains as may act

2
upon the hinges of the door while held in any position by said holder. Furthermore the described location of the holder facilitates its adjustment or removal and avoids 5 the necessity for the use of a step-ladder or the like, in attaching or detaching the said holder.

The construction is one that achieves a maximum simplicity, avoiding necessity for 10 ropes, chains or pulleys, and the like, and is consequently adaptable to manufacture at low cost.

What I claim is:—

1. The combination with a hinged door 15 and its frame, of a bar pivoted at its inner end upon said frame and extending toward the free edge of the door, and a bracket attached interiorly to said door formed with an opening slidably receiving said bar, and 20 further formed with a notch in the wall of said opening, said bar being formed in its outer portion with a notch engageable in an opened position of the door with the notch of said bracket to maintain said position.

2. The combination with a hinged door and its frame, of a bar pivoted at its inner end upon said frame and extending toward the free edge of the door, the lower portion 30 of said bar being reduced in width at its outer end and formed with a notch in said portion, and a bracket interiorly attached to the door formed with an opening slidably receiving said bar, an edge of said opening 35 being engageable by the notch of the bar in

an opened position of the door to maintain said position.

3. The combination with a hinged door and its frame, of a bracket mounted upon said frame, a bar having a downturned inner end pivotally engaging said bracket and being formed with an abutment at its outer end, the lower portion of said bar being reduced in width at its outer end, said bar being freely removable from said bracket, and a second bracket interiorly attached to said door and slidably engaged by said bar, said abutment of the bar being engageable with the second bracket in an opened position of the door to restrain the door from further opening movement.

4. The combination with a hinged door and its frame, of a bar pivoted at its inner end upon said frame and extending interiorly of the door toward the free edge of 55 the door, the lower portion of said bar being reduced in width at its outer end and formed with a notch in said portion, and a bracket interiorly attached to the door formed with an opening slidably receiving said bar, an 60 edge of said opening being engageable by the notch of the bar in an opened position of the door to maintain said position, and means carried by said bracket for clamping the bar to the bracket in a selective position 65 of the door.

In testimony whereof I sign this specification.

WESLEY G. WINANS.
